UNITED STATES PATENT OFFICE.

GRACE D. STURGES, OF SANTA MONICA, CALIFORNIA.

CARRYING CASE.

Application filed May 31, 1921. Serial No. 473,639.

To all whom it may concern:

Be it known that I, GRACE D. STURGES, a citizen of the United States, residing at Santa Monica, in the county of Los Angeles and State of California, have invented certain new and useful Improvements in Carrying Cases, of which the following is a specification.

My invention has reference more particularly to a carrying case, in which receptacles are hinged to a flat member so as to fold thereunder into a compact form and are adapted when unfolded to support the flat member at an elevation and thus form a table.

The principal objects of my invention are to provide a carrying case which folds into a compact form so as to be easily carried, and may be opened up to serve as a table; to provide receptacles which fold under the table top and open out to support the latter at an elevation; to fold the receptacles close together under and substantially parallel with the top so as to form a solid flat package, which is convenient to carry; to provide facilities for carrying the folded structure and in general, to provide an improved carrying case of simple construction, which folds into a very compact and convenient form and is adapted to be used for a great variety of different purposes.

On the drawings—

Fig. 1 is a side view of the carrying case open and ready for use.

Fig. 2, a similar view thereof, when folded.

Fig. 3, a transverse sectional view on the line 3—3 of Fig. 1.

Fig. 4, a fragmentary top view of one end of the carrying case showing the cover of the compartment open.

Fig. 5, a perspective view of a first aid kit embodying my invention, said kit being opened out ready for use.

Fig. 6, a perspective view of the first aid kit folded up and enclosed in a wrapper, and

Fig. 7, a view looking at one end of the kit when folded as shown in Fig. 6.

Referring to Figures 1 to 4 inclusive, which show a carrying case suitable for use as a picnic hamper, the reference numeral 1 indicates a flat rectangular member which has a receptacle 2 hinged thereto at each end, each of the latter being elongated as shown so that when positioned at right

angles to the member 1, they support the member 1 at a suitable elevation to form a table. Each of the receptacles 2 has a cover 3 hinged thereto at the outer side as indicated at 4 and provided with straps 5 at 60 the opposite side, which connect with buckles 6 or other fasteners on the receptacle 2 so as to hold the cover 3 in the closed position.

Each receptacle 2 is connected to the table 65 top 1 by a pair of spaced hinges 7, which hold the receptacles at a short distance from the end of the table top and afford a slot therebetween for the straps 5, and these hinges are connected to the receptacles 2 at 70 a short distance from the upper ends thereof.

Each of the receptacles 2 is connected to the underside of the table top 1 by means of a folding brace comprising the links 8 75 and 9, which are pivoted together at a laterally off set point as indicated at 10 and provided with a spring 11, which holds the links in either the extended or folded positions. In the extended position, shown in 80 Fig. 1, the ends of the links 8 and 9 are butted together and held against pivotal movement by the tension of the spring 11 which, however, permits breaking of the joint 10 and swinging of the links to the 85 position shown in Fig. 2 in which position the spring 11 serves to hold the links 8 and 9 in the folded position. Thus, by the folding of the links the receptacles are swung inwardly under the table top 1 with the 90 lower ends brought close together and a compact arrangement thus afforded so that the case may be readily carried or packed away.

To afford a handle, one of the receptacles 95 2 may be provided with a loop or ring 12, and a handle strap 13 has a snap fastener 21 at each end which connect with the loops or rings 12.

This case may be constructed with reed or 100 wicker receptacles 2, if desired, and in such cases I prefer to use a fabric case in which the folded carrying case is inserted so as to prevent dust etc. from sifting into the receptacles through the woven walls. When 105 the fabric case or envelope is employed, a handle may be provided on the fabric case and the handle, such as shown at 13, in Fig. 2, is then omitted.

This invention is also useful for a variety 110

of other purposes such for example, as a first aid kit as shown in Figs. 5 to 7 inclusive, in which the reference numerals 14 and 15 indicate packages of gauze, adhesive or other materials, which are connected together by a strip of card board 16. This strip 16 has portions 17 at the opposite ends bent laterally and secured to the side walls of the packages 14 and 15 so that the latter may be folded together under the card board 16 to form a compact package as shown in Fig. 6 or may be opened out as shown in Fig. 5 so that the packages 14 and 15 at the ends of the card board 16 afford a support for the latter and provide a small table, which may be used to support instruments and other articles. The packages may, if desired, be divided into a number of separate compartments as shown at 18 and 19 in Fig. 5, and these compartments are arranged so that the covers open upwardly when the packages are opened out and afford convenient access to the interior. This first aid kit may be enclosed in the folded condition in a sanitary wrapper 20, which not only serves to keep the contents clean but also holds the device in the folded condition.

While I have shown and described my invention in a preferred form I am aware that various changes and modifications may be made without departing from the principles of my invention, the scope of which is to be determined by the appended claims.

I claim as my invention:

35 1. In a device of the class described, the combination of a pair of spaced receptacles, and a shelf member extending between and pivoted to the receptacles adjacent the top thereof so that the latter fold under the shelf member, and means for releasably holding the receptacles in the unfolded position.

2. In a device of the class described, the combination of a shelf member having a receptacle pivoted thereto at each end for holding the shelf member in an elevated position and adapted to fold thereunder, said receptacles being provided with openings at the top closed by removable covers, which latter when closed over the openings form an extension of the shelf. 45

3. In a device of the class described, the combination of a pair of spaced receptacles, a shelf extending between and having the opposite ends hinged to the side walls of the receptacles so that the latter fold toward one another under the shelf and means for holding the receptacles in both the folded and unfolded positions. 50

4. In a device of the class described, the combination of a pair of spaced receptacles having a shelf extending between and pivoted to the receptacles near the upper ends thereof so that the latter support the shelf in an elevated position and are adapted to be folded toward one another under the shelf, and a collapsible brace extending between remote portions of each receptacle and the shelf for holding the receptacles at right angles to the shelf and adapted, when collapsed, to permit the receptacles to be folded 65 toward one another to a position under the shelf. 70

5. In a device of the class described, the combination of a pair of spaced receptacles, a shelf extending between and pivotally connected to each receptacle near the top so that the latter fold toward one another under the shelf, and means detachably connecting adjoining portions of the receptacles when folded under the shelf and serving as a carrying-handle for the device. 75

GRACE D. STURGES.
